UNITED STATES PATENT OFFICE.

EDWARD O'TOOLE, OF GARY, WEST VIRGINIA.

MINING-MACHINE.

1,151,383.

Specification of Letters Patent. Patented Aug. 24, 1915.

Application filed June 11, 1907. Serial No. 378,378.

To all whom it may concern:

Be it known that I, EDWARD O'TOOLE, of Gary, in the county of McDowell and State of West Virginia, have invented certain new 5 and useful Improvements in Mining-Machines, of which the following is a specification.

The object of this machine is to cut headings or passageways in mines, and when 10 used in coal mines of which the output is small or crushed coal, to sub-divide and mine the coal, and thus save the expense of crushing.

Although the machine is designed with 15 more particular reference to coal mining than to other uses, it is not limited to such particular use, but may be employed in any kind of mine or subterranean work where passages are to be made through solid rock, 20 mineral or other refractory material.

More especial objects are to provide a machine which may be driven forward by its own power as fast as the material in front of it is cut away; which can be operated so 25 as to remove the material from the entire extent of the opposing material at the end of a passageway; which has self-contained conveying means for carrying away the 30 broken material removed; and a simple arrangement of driving connections which can be independently thrown into gear so as to drive the several parts of the machine either independently or simultaneously.

Of the accompanying drawings,—Figure 35 1 represents a side elevation of the main part of a mining machine embodying the principles of my invention, in their preferred form. Fig. 2 represents an elevation of the rear portion of the conveyer extending away 40 from the machine, together with cars arranged to receive the material discharged from the conveyer. Fig. 3 represents a plan view of the part of the machine shown in Fig. 1. Fig. 4 represents a horizontal sectional view, on an enlarged scale, showing in detail the mechanism for operating the cutting devices of the machine. Fig. 5 represents a sectional front elevation of the mechanism for propelling the machine forward. Fig. 6 represents a horizontal section 45 of the mechanism for driving the conveyer and car-hauling device. Fig. 7 represents a detail plan view of the steering means for the machine. Fig. 8 represents a 50 cross-section showing on a larger scale a de-

tail of the conveyer. Fig. 9 is a detail elevation partly in section of the gears by which oscillation of the cutter head is effected. Fig. 10 is a fragmentary elevation partly in section showing the detachable connection between the frame of the machine and the conveyer section thereof. Fig. 11 is an elevation of the guide for the cutter head steadyng roll. Fig. 12 is an elevation showing in detail the cutter head frame. Fig. 13 is a detail elevation of one of the cutter chain guides.

The same reference characters indicate the same parts in all the figures.

The machine consists of a box-like frame 70 composed of plates, straps, and stiffening angle irons. The plates 1 and 2 constitute the sides of the main frame, while the plate 3 constitutes the front thereof. The latter plate is bent approximately into a quarter 75 circle and has secured to it at its opposite side edges the plates 4 and 5 which inclose a space to receive part of the swinging cutter-head frame and the driving motor.

The machine is supported by four traction 80 wheels 6 which are secured upon the ends of axles 7 and 8.

Pivoted in the space between the plates 3 85 and 5 is a cutter-head frame 9 which consists of the side plates 10 and 11, a bar 12 connecting them at their rear ends, and a plate 13 connecting the forward ends thereof. The pivotal axis upon which the cutter head is mounted is the back gear shaft 14 of a driving motor 15. The connection between 90 the motor armature shaft and the shaft 14 is indicated in Fig. 3 by the dotted-line gearing 16 17.

The forward part of the cutter-head frame 95 is stiffened by vertical plates 18 and has at its upper and lower extremes the guides 19 and 20 for the cutters 21. The upper guide is formed by plates 22 and 23, and the lower one by plates 24 and 25 held at the proper distance apart by guide wheels hereinafter described, and plates 27 and 28. To the guides are secured respectively, the plates 29 and 30 which hold the wheels hereinafter 100 described, which drive the cutters, which plates are fastened to center bars 31 and 32 105 respectively, while the latter are connected together by bolts 31^a and fastened at their ends to the plate 13 by bolts 31^b. The chain guides are also detachably fastened to the plate 13 by angles 13^a and lines of bolts 13^b. 110

Transversely passing through the cutter-head is a shaft 33 journaled in the sides of the cutter-head frame and passing between the center bars 31 and 32 which are spread apart for that purpose and also to receive a center bearing block 34. Secured to one side plate of the cutter-head frame is a sleeve 35 which surrounds the hub 36 of a gear 37 which is loosely mounted on one end 10 of the drive shaft 14, while the other side plate carries a sleeve 38 pivotally mounted on the shaft 14. The cutter head is capable of oscillating about the center of shaft 14 by reason of the fact that these sleeves are free 15 to turn.

The mechanism for causing the cutter head to be oscillated and the cutters to be simultaneously driven is as follows: Keyed to the shaft 14 is a clutch 39 having pins or 20 studs 40 adapted to enter spaces 41 in the web of the gear 37. This clutch is shifted axially by a cotter 42 which passes through a slot in the shaft and through a rod 43 entering the shaft endwise. This rod is controlled by a lever 44 which engages between collars or shoulders 45 on the rod and so is 25 enabled to move it endwise. On the outer end of the hub or sleeve 36 is cut a small pinion 46 which meshes with a gear 47, while on the outer end of shaft 33 is secured 30 a crank arm 48. The gear 47 is mounted to turn upon a stud 49 carried in a plate 50 which is secured to the sleeve 35 and has secured to it a bearing 51 for the end of shaft 33. Gear 47 therefore occupies an invariable 35 relation with respect to the other parts carried by the cutter head, and swings with these parts about the shaft 14. A connecting rod 52 is attached to a crank-pin 53 on the gear 47 and to a wrist-pin 54 on the arm 48. Thereby an oscillation of shaft 33 is produced by the rotation of gear 47. Surrounding the sleeve 35 is the hub 55 of a gear segment 56, said hub being secured to the side 40 plate 4 of the main frame so as to be held stationary. Upon the sleeve 38 is a similar gear segment 57 fixed to the side plate 5 of the frame. With these segments mesh co-operating 45 segments 58 and 59 secured to the shaft 33. Thus the oscillation given to shaft 33 by the connecting rod causes the segments 58 and 59 to roll upon the fixed segments and thereby oscillates the cutter head, swinging it up and down. The distance of the wrist-pin 54 from the shaft is governable by a 50 screw 60, while the connecting rod is variable in length, as shown in Fig. 1, so that both the distance of swing of the cutter head and the location of its path may be varied at will.

The cutters 21 are carried by endless chains 61 and 62 carried in the guides 19 and 20 respectively. The former passes around guide sprockets 63 at the ends of the 55 guide, take-up wheels 64, and a drive wheel

65. The other chain passes around similar guide and take-up wheels and a driving sprocket 66. To each of these driving sprockets is secured a bevel pinion 67 meshing with a bevel pinion 68 formed upon the 70 end of a sleeve 68a. Also formed upon this sleeve is a gear 69 which meshes with the gear 37 previously described. Thus the motor drives the cutter-carrying chains at the same time that it oscillates the cutter head. 75 As these chains are driven from opposite sides of the pinions 68, they travel in opposite directions, and they are arranged so as to extend across the entire front end of the cutter head parallel to each other, and one above the other. As the cutters travel horizontally while the head swings vertically, it is apparent that the cutters of one series will make a number of parallel grooves extending on a slant, while the cutters of the second series will make similar grooves, but oppositely inclined. The grooves will therefore cross each other, and also the same cutters in going down will cross the grooves which they made coming up. 80 Thereby the whole face of the mineral in front of the machine is crisscrossed with grooves, and all the material is removed in a comparatively finely broken condition. 85

In order to take the thrust of the cutters there is mounted upon each of the cutter guides a roll which rests against the wall of the heading from which the cutters travel. That is, the thrust roll 70 on the upper chain guide bears against the right-hand wall of the heading because the upper series of cutters move to the left, while the roll 71 bears against the left-hand wall of the heading. These rollers are mounted yieldingly so as to give way when the width of the heading diminishes by reason of the cutters becoming worn away. If the rolls could not so yield, they would cause the cutter head to collapse. As appears in dotted lines from Fig. 3, each roll is journaled in a fork 72 on the end of a rod 73, and is pressed outwardly by springs 74 surrounding the rods and abutting against the side plates of the cutter-head frame. Beside each of the rolls is fastened an angular guide 75 which has a slot 75a to receive one end of the roll trunnion so as to keep the latter always radial to the path of the cutter head. 90

Each of the cutters is detachably mounted in the carrying chain, the latter being composed of alternate blocks and coupling links in the former of which the cutters are placed and held by set screws. Looseness in the chain is taken up by adjustment of the guide wheels 64, the pivots of which pass through slots 76 in the frame, in which slots they are adjustable. Nuts 77 allow the wheels to be clamped and held in adjusted position by friction. 100

On the end of the motor back gear shaft 105

14 is a sprocket 78 from which a chain 79 passes to a second sprocket 80 upon a counter-shaft 81. Thus the counter-shaft is driven by the motor, and in turn drives the traction wheels, the conveyer, and the cable drum by which cars are brought to and from the machine.

The conveyer is of the scraper type, and consists of a number of blades 82 of which 10 the ends are carried by chains 83 and 84 which pass over driving sprockets 85 on the conveyer head shaft 86. The blades pass over a bottom plate 87 which at its forward end slopes nearly to the floor of the heading and extends horizontally at its rear away 15 from the main part of the machine. Over this plate the conveyer blades push the broken material, which is prevented from falling off at the sides by angle irons 88 89 20 which form side walls. At the end of the conveyer the material is discharged, as shown in Fig. 2, into cars 90. Guide wheels 91 at the rear of the conveyer and 92 on the front axle 8 hold the ends of the conveyer in place, while intermediate sprockets 25 93 and 94 take up the slack and the latter holds the forward part of the conveyer in position to scoop up the loose material.

The conveyer head shaft 86 is driven by 30 the counter-shaft 81 through gears 95 and 96, of which the former is loose on the counter-shaft. A clutch 97 splined upon the counter-shaft permits the conveyer drive to be thrown into and out of gear when desired. This clutch is controlled by a hand lever 98.

The material broken and cut away from the end of the heading falls in a loose mass at the bottom, as shown in Fig. 1. In order 40 to push this out of the way of the wheels, plows 99 which run close to the floor of the heading are loosely engaged with the forward wheels by clips 100 and guards 101 extending around the wheels and fastened at 45 their ends to the frame. These plows clear a path for the wheels, pushing the material to either side. The latter is gathered toward the center of the machine by inclined scrapers 102 at the sides thereof. These 50 scrapers are pivoted at their inner ends by bolts or pins 102^a and held by tie-rods 103 to the frame so that their forward ends will not be arrested by irregularities in the walls of the head. If such an arrest should take 55 place, the scrapers would act as toggles to force the sides of the machine together. The outer ends of these scrapers are curved to conform with the curvature between the bottom and side walls of the passages. The 60 lower end of the conveyer guideway is formed by a plank 104 hinged to the lower end of plate 87 by hinges 104^a and held by bolts 105 which are connected to studs passing through the bearing boxes 106 of the 65 take-up wheel 94. These bearing boxes may

be raised in the guides 107 so as to raise the plank 104 and conveyer clear of the heading floor.

The rear end of the conveyer guide or trough is vertically adjustable by means of 70 the pivot pin 108 and screw 109. At this point the conveyer trough is made in two parts which are pivoted together and have ears 110 111 through which the screw 109 passes. This adjustment is provided for use 75 in following dips and rises. The conveyer can be taken apart at this point by simply removing the screw 109 and drawing out the coupling pin 108. A disconnection can also be made between the conveyer section 80 112 and the main part of the frame at the point 113, as the side plates of said conveyer section and frame are provided with flanges 112^a at their meeting edges, which are connected together by detachable fastenings 85 such as bolts 112^b. Thus the machine may be made more readily portable for transportation to different parts of a mine.

In order to drive the machine forward while the cutting is taking place, there is 90 provided upon the gear wheel 96 previously described, an eccentric crank-pin 114 to which is pivoted a connecting rod 115. The latter has a slot 116 in its end through which passes a pin 117 on a plate 118 loosely surrounding a longitudinally extending shaft 119 (see Fig. 5). Pivoted in the plate 118 are pawls 120 and 121 adapted to engage a ratchet wheel 122 keyed to the shaft 119. The latter carries upon it a worm 123 meshing with a worm wheel 124 on the rear axle 95 7 of the machine. On the end of this axle is a sprocket wheel 125 from which extends a chain 126 passing about a sprocket 127 on the forward axle 8. As the driving wheels 105 6 are keyed or fastened by set screws to the axles, they are thus all driven in unison.

The pawls 120 and 121 have square holes through which passes a squared pin 128 by which they are pivoted to the plate 118. 110 The pin 128 is loose enough to allow one pawl to rest against the end of a tooth, while the other is in the space between two teeth. The toes of these pawls are separated from each other by a distance which is an 115 odd multiple of half the tooth spacing so that when one pawl is engaged with the end of a tooth to advance the ratchet, the other rests half way between two teeth. This enables a finer feed to be given. When it is 120 desired to stop the forward movement of the machine, the pawls may be thrown back out of engagement with the ratchet. The machine may be fed forward simultaneously 125 with the cutting action or independently after a cut has been made by manipulation of the clutch 39 and the pawls, according to circumstances.

Loosely mounted on the rear axle is a rope or cable drum 129 which is driven at will by 130

the counter-shaft 81 through a clutch 130 splined to the shaft, a sprocket 131 loose thereon, chain 132, sprocket 133, and gears 134 and 135. The latter is fastened to the drum 129 and the former to a stud shaft on which the sprocket 133 is secured. The clutch 130 is thrown into and out of connection with a complementary clutch member on the sprocket wheel 131 by a lever 136 and a hand-operated link 137. By means of a cable 138 passing around the drum and a tail-sheave (not shown), the cars 90 may be hauled to or away from the machine.

The machine is steered by guide wheels 139 adapted to bear simultaneously against opposite sides of the heading. Each of these wheels is pivoted on a pin 140 carried in bars 141 attached to T-rods 142 which have round screw-threaded shanks 143. The latter pass loosely into the adjacent ends of pipes 144 and are adjusted to project the required distance therefrom by nuts 145 engaged with said threads and bearing against locking plates 146 which pass across the ends of the pipes 144. The locking plates 146 are provided to prevent the nuts being turned by the rotation of the pipes which is made to adjust them. These pipes pass through the machine and are threaded where they pass through the plate 1 and the nuts 147 secured to these plates. By means of rods set into the holes 148 in nuts attached to the pipes, the latter may be turned and so caused to move endwise across the machine, thereby setting the latter toward one side or the other of the passage. These steering wheels are particularly useful to prevent the machine skidding to the low side of the heading when cutting on inclined 40 seams.

Beside the traction wheels 6 are loose flanged wheels 149 which are adapted to run upon tracks when the machine is transferred from one part of the mine to another. To permit such transfer the traction wheels are removed from the axles, the steering wheels 139 removed by pulling them from their pipes 144, and the conveyer sections are taken apart and the cutter guides with their 50 wheels and center bars removed. The wheels 149 can then be placed upon the track which is laid to follow the machine closely and can be readily brought from one place to another.

In bringing the machine into the working place at the start it is run on the main track as far as that extends, and then is run over the end of the track, and dropping to the floor runs forward to the working place on traction wheels 6 under its own power, without any preliminaries whatever except slipping the traction wheels on the axles. Heretofore to the best of my knowledge, mining machines have never been provided with a 60 set of wheels that could run on the main

tracks. Machines have been built with large wheels for running on the bottom of the heading, but in moving to another part of the heading, these machines have had to be placed on trucks.

The construction of the conveyer chain is such as to allow it to be unhooked at any point, and thus the conveyer can be taken apart and readily put together again when desired. The construction previously described, of the cutter head, enables the latter to be also taken apart and assembled with a slight expenditure of time and labor. By removing the bolts 31^a, 31^b and 13^b, the chain guides with their bevel gears, chains and sprockets may be taken apart without disturbing any adjustments.

The power used is preferably electrical, the motor being any of the well-known types adapted to give the necessary amount of power. The motor is controlled by a controller 150 of the ordinary type. It will be seen that the controller crank 151, the handle of link 137, and the levers 98 and 44 are all close together so that they can be handled easily and all the mechanisms of the machine controlled by a single operator.

I claim:

1. A machine for cutting passage-ways in mines and dividing the material removed, comprising a swinging frame, means for swinging said frame, cutting devices movable in said frame at the end thereof transversely of the swinging movement thereof, whereby to remove the material from the entire area of the end of the passage, and propelling mechanism arranged and operated to advance the machine simultaneously with the removal of such material.

2. A machine for cutting passage-ways in mines and dividing the material removed, comprising a swinging frame, means for swinging said frame, cutting devices movable in said frame at the end thereof transversely of the swinging movement thereof, whereby to remove the material from the entire area of the end of the passage, propelling mechanism arranged and operated to advance the machine simultaneously with the removal of such material and conveying means arranged to gather such material and convey it to an elevated discharge point at the rear.

3. A machine for cutting passages in mines, comprising a cutter carrier, cutters held by and movable relatively to said carrier, means for moving the cutters in a predetermined direction in the carrier, mechanism for moving the carrier in directions transverse to that of the cutters, said mechanism being arranged to cause automatic reversal of the carrier at the ends of the latter's travel, supporting means for said cutter carrier, and mechanism for advancing said supporting means continuously without

limit, operating in connection with said means and mechanism by which said cutters and carrier respectively are moved, and at a rate proportional to the movement of the said cutters and carrier.

4. A machine for cutting passages in mines, comprising a cutter carrier, cutters held by and movable relatively to said carrier, means for moving the cutters in a predetermined direction in the carrier, mechanism for moving the carrier in directions transverse to that of the cutters, said mechanism being arranged to cause automatic reversal of the carrier at the ends of the latter's travel, a frame on which said cutter carrier is mounted, traction wheels supporting said frame, and mechanism operated in mechanical connection with the aforesaid means and mechanism for driving said traction wheels at a rate which bears a predetermined ratio to the rate of movement of said cutters and carrier, whereby the cutter carrier is advanced simultaneously with the removal of material by the cutters.

25 5. A machine for cutting passages in mines, comprising a body frame, traction wheels supporting said frame, a cutter head movably mounted on said frame, cutting means carried by said cutter head, driving mechanism constructed and arranged to actuate the cutter head and cutting means so as to remove mineral from the face of the opposed body of mineral, and connections from said driving mechanism for driving said traction wheels, whereby the machine is propelled at a rate in proportion to the speed of movement of the cutter head.

6. A mining machine comprising cutters arranged to travel in one direction, and automatic means for shifting the cutters with a continuous back and forth movement bodily in an intersecting direction, whereby they are caused to cut grooves inclined to both directions.

45 7. A mining machine comprising a cutter head, cutters guided thereby to travel in one direction across the face thereof, and automatically acting means for moving the cutter head continuously back and forth in a different direction at the same time, whereby a resultant movement is given the cutters which is inclined to both directions.

8. A mining machine comprising a cutter head, a plurality of connected cutters arranged and guided to travel in line across the face thereof, and means for simultaneously moving the cutter head transversely to the line of travel of the cutters, whereby the latter are caused to cut inclined parallel grooves in the opposing wall against which they are caused to act, said means being constructed to cause reversal of the cutter head automatically at the end of each of its movements.

65 9. A mining machine comprising a cutter

head, a plurality of cutters connected and arranged to travel in two oppositely-moving lines across the face of the cutter head, and means for shifting the cutter head transversely to the movement of the cutters and simultaneously therewith, whereby intersecting inclined grooves in parallel series are cut, combined with automatically acting means for driving the machine ahead as the material is cut away, and means for moving the cut material out of the way of the advancing machine.

10. A machine for cutting headings in mines, comprising a cutter head pivoted on a horizontal axis and extending the full width of the heading, means for swinging the head vertically back and forth about said pivot, and automatically reversing its motion at the end of each swing, and a series of cutters extending in line across the face of the head and connected to travel transversely to the movement of the head.

11. A mining machine comprising a main frame, a cutter head mounted to swing pivotally in said frame, a driving motor, connections including a constantly rotating crank and a connecting rod connected to said cutter head, whereby the head is caused by said motor to move back and forth about its pivot, and to be stopped and started gradually at each reversal, and cutters actuated by said motor to travel upon the head.

12. A mining machine comprising a main frame, a cutter head mounted to swing pivotally in said frame, cutters mounted to travel on said head and projecting therefrom in position to cut away material opposed thereto, a driving motor, and connections driven by the motor whereby the latter may drive the cutters, and driving connections for simultaneously oscillating the head with approximately harmonic motion.

13. A mining machine comprising a main frame, a cutter head mounted to swing pivotally in said frame, cutters mounted to travel in guides in said head, a motor, a gear fixed concentrically with the pivotal axis of the head, a gear rotatably mounted on the head in mesh with said fixed gear, and connections driven by the motor for turning said rotatable gear at alternately increasing and diminishing speeds and thereby swinging the head back and forth with approximately harmonic motion.

14. A mining machine comprising a main frame, a cutter head pivotally connected to said frame and having cutter guides, connected series of cutters mounted to travel in said guides transversely to the motion of said head about its pivot, a stationary gear element, a rotary gear element meshing therewith and carried by the head, and means for continuously oscillating said latter gear element with alternately accelerating and diminishing speeds, whereby the

- head is swung automatically back and forth and gradually stopped and started at each reversal of its motion.
15. A mining machine comprising a main frame, a cutter head pivotally connected to said frame and having cutter guides, connected series of cutters mounted to travel in said guides transversely to the motion of said head about its pivot, a stationary gear element fastened to said main frame concentrically with the pivot of said head, a rotary gear element meshing therewith and carried by the head, and means for continuously oscillating said latter gear element at a diminishing rate of speed as it approaches each point of reversal, whereby the head is swung back and forth automatically and gradually started and brought to rest in each direction.
16. In a mining machine having a cutter head pivotally mounted thereon and a connected series of cutters arranged to travel in said head transversely of the pivotal motion thereof, a stationary gear element concentric with the pivot of said head, a movable gear element meshing therewith and mounted pivotally on the cutter head, a rotary driving crank, and a connecting rod joined with said crank and with said movable gear element so as to oscillate the latter, whereby said element is caused to roll back and forth on the stationary gear element and correspondingly swing the cutter head.
17. In a mining machine having a cutter head pivotally mounted thereon and a connected series of cutters arranged to travel in said head transversely of the pivotal motion thereof, a stationary gear element concentric with the pivot of said head, a movable gear element meshing therewith and mounted pivotally on the cutter head, a rotary driving crank, a connecting rod joined with said crank and with said movable gear element so as to oscillate the latter, whereby said element is caused to roll back and forth on the stationary gear element and correspondingly swing the cutter head, and adjustments for shifting the positions in which the motion of the head is reversed and for varying the amplitude of its oscillations.
18. In a mining machine having a cutter head pivotally mounted thereon and a connected series of cutters arranged to travel in said head transversely of the pivotal motion thereof, a stationary gear element concentric with the pivot of said head, a movable gear element meshing therewith and mounted pivotally on the cutter head, a rotary driving crank, a connecting rod joined with said crank and with said movable gear element so as to oscillate the latter, whereby said element is caused to roll back and forth on the stationary gear element and correspondingly swing the cutter head, and independent adjustments whereby the amplitude of oscillation of the head may be varied, and whereby the positions in which its motion is reversed may be shifted without changing the extent of its motion.
19. In a mining machine having a cutter head pivotally mounted thereon and a connected series of cutters arranged to travel in said head transversely of the pivotal motion thereof, a stationary gear element concentric with the pivot of said head, a movable gear element meshing therewith and mounted pivotally on the cutter head, a rotary driving crank, and a connecting rod joined with said crank and with said movable gear element so as to oscillate the latter, whereby said element is caused to roll back and forth on the stationary gear element and correspondingly swing the cutter head, said rod being adjustable in length to alter the locations in which reversal of the motion of the head occurs.
20. In a mining machine having a cutter head pivotally mounted thereon and a connected series of cutters arranged to travel in said head transversely of the pivotal motion thereof, a stationary gear element concentric with the pivot of said head, a movable gear element meshing therewith and mounted pivotally on the cutter head, a rotary driving crank, a connecting rod joined with said crank, and an arm with which said rod is engaged, connected to said movable gear element and having a greater length than the driving crank, so that the latter element is caused to oscillate and roll back and forth on the stationary element, correspondingly swinging the cutter head.
21. In a mining machine having a cutter head pivotally mounted thereon and a connected series of cutters arranged to travel in said head transversely of the pivotal motion thereof, a stationary gear element concentric with the pivot of said head, a movable gear element meshing therewith and mounted pivotally on the cutter head, a rotary driving crank, a connecting rod joined with said crank, an arm connected with said movable gear element, and a wrist pin carried by said arm, with which said connecting rod is engaged, said pin being adjustable on the arm to vary its distance from the axis, whereby the arm and movable element may be oscillated in varying degree and the cutter held correspondingly swung in a path of varying extent.
22. A mining machine comprising a main frame, a cutter head frame, a shaft journaled in said main frame and upon which said cutter head frame is arranged to swing pivotally, a motor carried by said cutter head frame connected to drive said shaft, a gear fixed to the main frame co-axially with said shaft, a shaft journaled in the cutter head frame, a gear fastened thereon in mesh with said fixed gear, driving connections be-

5 between the motor and said last-named shaft for oscillating the latter and thereby swinging the cutter head frame, and cutters mounted and caused to travel on said cutter head frame in directions transverse to the oscillations thereof.

23. A mining machine comprising a main frame, a cutter head frame, a shaft journaled in said main frame and upon which 10 said cutter head frame is arranged to swing pivotally, a motor carried by said cutter head frame connected to drive said shaft, a gear fixed to the main frame co-axially with said shaft, a shaft journaled in the cutter 15 head frame, a gear fastened thereon in mesh with said fixed gear, driving connections between the motor and said last-named shaft for oscillating the latter and thereby swinging the cutter head frame, adjustable to vary 20 the position and length of swing thereof, and cutters mounted and caused to travel on said cutter head frame in directions transverse to the oscillations thereof.

24. A mining machine comprising a main 25 frame, a cutter head frame, a shaft journaled in said main frame and upon which said cutter head frame is arranged to swing pivotally, a motor carried by said cutter head frame connected to drive said shaft, 30 a gear fixed to the main frame co-axially with said shaft, a shaft journaled in the cutter head frame, a gear fastened thereon in mesh with said fixed gear, driving connections between the motor and said last- 35 named shaft for oscillating the latter and thereby swinging the cutter head frame, endless cutter carriers mounted to travel in guides in the cutter head frame, drivers therefor, and a gear loosely mounted on the 40 last-named shaft driven by the motor for actuating the drivers.

25. A mining machine comprising a main frame, a cutter head frame, a shaft journaled in said main frame and upon which 45 said cutter head frame is arranged to swing pivotally, a motor carried by said cutter head frame connected to drive said shaft, a gear fixed to the main frame co-axially with said shaft, a shaft journaled in the cutter 50 head frame, a gear fastened thereon in mesh with said fixed gear, cutter carriers mounted to travel in said cutter head frame, gearing for driving the same, and gears loose on the motor-driven pivot shaft and engageable 55 therewith, connected respectively with the second shaft and the cutter drive, for causing the cutter head frame and cutters to be moved simultaneously.

26. A mining machine comprising a main 60 frame, driving wheels on which the same is supported, a pivoted cutter head frame arranged to oscillate up and down, cutters mounted to travel therein transversely to the direction of oscillation thereof, a motor, and 65 independently disconnectible driving con-

nections between the motor and the driving wheels and the cutter head, whereby the machine may be caused to cut and to be advanced at the same time or independently, at will.

27. A mining machine comprising a main frame, a back-and-forth moving cutter head, cutters carried by said head and movable transversely of the movement thereof, wheels supporting said frame, a driving motor, connections operated by said motor for moving said cutter head back and forth, means for moving said cutters on the head, also operated by said motor, and slow speed gearing driven by the motor for turning 80 said supporting wheels and advancing the machine.

28. A mining machine comprising a main frame, a back-and-forth moving cutter head, 85 cutters carried by said head and movable transversely of the movement thereof, wheels supporting said frame, a driving motor, connections operated by said motor for moving said cutter head back and forth, means for moving said cutters on the head, also operated by said motor, a worm wheel connected to said supporting wheels, a worm meshing therewith, and ratchet and pawl mechanism operated by the motor for rotating said worm and thereby driving the machine at a 90 slow speed.

29. A mining machine comprising a main frame, a back-and-forth moving cutter head, cutters carried by said head and movable 100 transversely of the movement thereof, wheels supporting said frame, a driving motor, connections operated by said motor for moving said cutter head back and forth, means for moving said cutters on the head, also operated by said motor, by which the material opposed to the machine is cut and removed from the entire opposing surface, and a conveyer arranged to travel close to the ground and upward and rearward from the machine, for carrying away the material dislodged by the cutters.

30. A mining machine comprising a main frame, a back-and-forth moving cutter head, cutters carried by said head and movable 105 transversely of the movement thereof, wheels supporting said frame, a driving motor, connections operated by said motor for moving said cutter head back and forth, means for moving said cutters on the head, also operated by said motor, by which the material opposed to the machine is cut and broken away over its entire extent, driving connections between the motor and supporting wheels by which the machine is driven forward at a slow speed as the cutting progresses, plows arranged in advance of the forward wheels to displace the loose material from in front of the same, a conveyer arranged with its forward end near the 120 ground and traveling upward and rearward 125

from the machine for removing the loose material, and a scraper for gathering the material together where it can be acted upon by said conveyer.

5 31. In a mining machine, a main frame, a drive shaft, a motor connected to actuate said drive shaft, a cutter head pivoted coaxially with said drive shaft, a counter shaft journaled in said cutter head, gear segments 10 secured thereto, stationary gear segments fixed to the main frame coaxially with the drive shaft, mechanism actuated by the drive shaft arranged to oscillate the counter shaft and thereby swing the cutter head, an

endless chain carrying cutters along the forward end of the cutter head, a driving sprocket for said chain, intermeshing bevel gears respectively fixed thereto and journaled on the head, and gearing between said drive shaft and said bevel gears, whereby 20 the latter are operated and the chain caused to travel.

In testimony whereof I have affixed my signature, in presence of two witnesses.

EDWARD O'TOOLE.
